CLAIM

The ornamental design for a baby car seat cover as shown and described.

DESCRIPTION

FIG. 1 is a front left perspective view of the baby car seat cover installed on a baby car seat and showing my new design;

FIG. 2 is a front view thereof;

FIG. 3 is a rear view thereof;

FIG. 4 is a right view thereof;

FIG. 5 is a left view thereof;

FIG. 6 is a top view thereof;

FIG. 7 is a front view thereof, the cover shown in an uninstalled condition; and,

FIG. 8 is a rear view thereof, the cover again shown in an uninstalled condition.

The broken line showing of portions of the baby seat cover is included for the purpose of illustrating environmental structure and forms no part of the claimed design. The dotted line showing portions of the baby seat cover is included for the purpose of illustrating stiches and forms no part of the claimed design.
